PACK-ANNEALING BED

Edward C. Peterson, Narberth, and Edward T. Peterson, Reading, Pa., assignors to Birdsboro Steel Foundry & Machine Company, Birdsboro, Pa., a corporation of Pennsylvania

Application September 2, 1941, Serial No. 409,260

17 Claims.

(Cl. 80—42)

The invention relates to packs for facilitating pack-annealing.

A purpose of the invention is to prevent flats from falling forward and overlapping upon a pack-annealing bed.

A further purpose is to prevent upward divergence of flats on a pack-annealing bed, holding them together to maintain uniform annealing.

A further purpose is to pack flats, plates or strips, hereinafter called flats, on edge close together for pack-annealing upon a support, nearly enough horizontal so as to present a non-slip surface to the lower flat edges, sloping the flats rearwardly and upwardly to avoid having them fall forward on the annealing bed, or holding the upper edges of the front flats to prevent this, so that as the flats are transferred progressively toward a carry-over conveyor they slide off from the pack or may be tilted off from the pack by hand.

A further purpose is to support the upper edge of each rear flat or strip of a pack-annealing group of flats by latches or catches, adjustable in height according to the widths of the flats, so as to hold the upper rear edges of the successive flats against backward tilting movement while permitting other flats subsequently to be pushed forward beneath the latches and to be similarly held.

A further purpose is to retard the upper parts of the front flats of a pack until the flats are ready to drop or to be thrown from the front end of the pack bed upon the carry-over conveyor, beginning this when the pack is being built up and continuing it through subsequent operation.

A further purpose is to hold the front end of a pack yieldingly by its upper edges and to release the flats from the pack and concurrently guide them outwardly at their lower edges.

A further purpose is reliably to prevent the upper edge of each front flat of a pack from forward movement until it reaches the forward end of the pack bed by retarding the upper edge against falling forward.

With packs in which the angle of the surface of the flats with respect to the pack support is such that the flats if unrestrained will or may fall forward about their lower edges, a further purpose is to hold the upper part of each front flat against forward turning movement during the build-up of the pack and subsequently and to use a front sloping surface of the pack bed concurrently or later to shift the lower edge of the flat outwardly.

Further purposes will appear in the specification and in the claims.

The invention has been illustrated by applying it to forms of cooling beds which are practical, effective and successful and which at the same time well illustrate the invention.

Figure 1 is a vertical, longitudinal section and partial side elevation of one cooling bed to which the invention is applied, a carry-over horizontal bed being shown in dot-and-dash.

Figure 2 is a vertical longitudinal section of a second form of cooling bed in which the present invention is embodied and with which it cooperates to advantage, the carry-over horizontal bed again being shown in dot-and-dash.

Figure 2a, 2b and 2c are a fragmentary side elevation, a fragmentary top plan view and a modified fragmentary elevation, respectively, of the structure of Figure 2.

Figure 3 is a fragmentary side elevation to illustrate the prior art.

In the drawings similar numerals indicate like parts.

The invention is shown as a part of a handling system which necessarily involves each, a run-in conveyor, kick-off means, guides for the shapes kicked off, and guides to a carry-over section, none of which is intended to be claimed separately herein. It concerns the control of flats upon a pack-annealing bed.

In the prior art, the friction of the flats against the upper pack bed surface has retarded the movement of the bottom edges of the flats along the bed from rear to front. This has been accentuated by the fact that whatever retardation has been offered to the progress of the flats along the bed, has been at the lower parts of the flats during initial building up of the pack and subsequently.

In Fiske Patent No. 1,921,353 the retardation due to the friction at the bottom of the flats and the retardation substantially in line with the bottoms of the flats due to the dogs which have almost disappeared below the pack, hold the lower parts of the pack together in the main, but the upper edges of the pack meantime are unrestrained, with the result that they have tended to diverge and ultimately have diverged to such an extent that before the front end of a pack is reached in many cases, the flats fall down and overlap, the rear flats overlapping the front flats to such an extent that pulling the lower (front) flats out to clear them from the pack-annealing bed has presented a difficult problem.

Both the Fiske et al. Patent 1,954,123 (Figure 4) and the Fiske patent above (Figure 9), have recognized the overlapping of the flats at the front end of the bed. This has been recognized also in a patent which does not show the restraint of dogs at the front of the pack, namely, Fiske Patent 1,904,434 (Figure 11).

Not only is the overlapping of the flats on the front of the bed objectionable, but the divergence of the flats throughout whatever portion of the front end of the bed results in differential annealing of the flats themselves, the width of the flats annealing more fully where the flats are held close together at the bottom and progressively cooling more rapidly toward the upper edges of the flats as the flats diverge upon the bed.

Our invention contemplates protecting against both of these objections by maintaining the flats in contact or substantially in contact throughout the entire length of the bed, holding them together either by sloping them so they lean upwardly and rearwardly or by applying retardation to the upper front edges of the pack so that in either event they do not fall forward until they reach the point of discharge and fall over or are pulled over the edge.

The conveyor at the upper right hand of each of Figures 1 and 2 includes, among other structure supported upon a fixed frame 10, the usual plurality of motors 11, feed rolls 12, and bearings 13, spaced at intervals along the length of the rolled stock handled, forming a lead-in conveyor system by which the shapes rolled are fed lengthwise toward the observer in these figures until the shapes in turn reach the position at which they are to be transferred from the lead-in conveyor toward the bars of the carry-over section.

One shape, a flat 14 is shown upon the run-in conveyor, in Figures 1 and 2, ready to be shoved off by the kick-off arm 15 of one of duplicate units. The arm is carried by vertical shaft 16 and is operated by any lever 17, plunger 18 pivoted at 19 to the lever, and motor not shown. The shaft 16 is mounted in suitable fixed bearing 20.

The kick-off lever arm 15 swings in horizontal planes and carries shapes to the left in Figures 1 and 2, free from the run-in conveyor. The shapes in turn are thus slid along a fixed receiving apron 21 sloping downwardly at 22, and notched at 23. The notch receives the sections and holds them intermediately.

In Figure 1 shapes are carried from the notch 23 by dog 25 or dog 26 mounted upon rocker shaft 24. Dogs of the general type of 26 appear in the joint patent above Number 1,954,123 but in this patent they cooperate with a tilting bed not shown in Figure 1.

The shaft 24 is supported from the frame structure by bearings 27 and the dogs operate through openings in the bed. They are mounted on jaws 28 and 29 clamped about the shaft by means of fastenings at 30. The dogs 25 and 26 are alternative and are not used at the same time.

The shaft 24 extending the full length of the bed is rocked by means well known but not shown and, if dogs 25 are to be used, they are turned about the shaft or the shaft is turned until the surfaces 31 of dogs 25 lie in about the angular positions in which surfaces 32 of dogs 26 are shown in Figure 1. Dogs 25 are well suited for use to transfer shapes of any character when pack-annealing is not intended.

When the shaft 24 is rocked in counter-clockwise direction in Figure 1 the shape will be car-

ried up along the curved walls 33 of the portion 34 of the apron or bed to some position 35 upon the straight support 36 where the shape is left when the dogs rock in the opposite direction, 5 back to their original positions.

From any position 35 the shape is carried to the left in Figure 1 beyond the surface 36 by pusher heads 37 upon pusher bars 38, so that the shape slides down the sloping surface 39 and 10 lands upon the carry-over conveyor at the left of the figure. The pusher bars, spaced at intervals along the length of the mill, carry racks 40 operating within fixed guides 41.

The racks 40 are engaged by pinions 42 carried by shaft 43 in bearings 44. The shaft is turned in either of opposite directions by any suitable motor not shown. With counter-clockwise movement of the shaft in the illustration, the racks, pusher bars and pusher heads are shifted to the left to carry the shapes toward the left ends of the surface 36 so as to start the shapes, one at a time, falling off the pack bed beyond the corner 46 and landing upon the carry-over conveyor at 47.

It will be noted that, when not in use the pusher heads lie out of line of travel of the shapes as they pass from the run-in conveyor to the notches 23.

In Figure 2 the table is intended to tilt from pack-annealing position to provide a slope which will cause feeding downwardly of shapes which are not intended to be pack-annealed.

All shapes which are not intended for pack-annealing are carried by dogs 25 about the curved surface 33' from notch 23' and are thereafter slid downwardly upon the surfaces 36' in the tilted position of the table, as seen in dot and dash in Figure 2.

The tilting of the table in Figure 2 is not new, 40 nor is the mechanism by which this tilting is effected; however it is new to lift the table to an upwardly tilted position or to construct a table where the upper surface of the table is approximately horizontal.

The table is tilted by mounting it upon beams 43 and tilting the beams by crank arms 49, straps 50 and pitmans 51 connected with the beams by pivot pins 52 and eyes 53 in rods 54. The lever arms are thrown by turning shafts 55 in clamps 56, subsequently tightened. The strap and clamps are fastened by bolts 57.

Each pitman includes a turn buckle 58 by which adjustment of the height of the pack bed may be varied.

The objectionable overlapping of flats, one over the top of another in the existing art, exemplified in Figure 3, is made worse in some cases by the fact that the flats are pack-annealed in positions with their widths unstable or decidedly sloping upwardly and forwardly, which is not helped by the yielding retardation of the pack at the lower forward face of the pack. Both the direction of the slope of the individual flats and the yielding lower edge retardation as distinguished from yielding top retardation contribute to a forward and downward turning of the upper edges of the individual flats (as compared with their lower edges) upon the pack-annealing bed causing the later flats to fall upon preceding flats.

The edge-supported flats in the preferred form slope upwardly and rearwardly and are retained yieldingly along their upper rear edges by latches or catches to hold each rear flat as and when it is placed in its rear position, and rest the lower

edge of each flat upon a surface which makes a non-skid angle with the lower part of the flat. With a substantially horizontal supporting surface, ample upward and rearward slope of the flat, to keep it from falling, can be had without having the flat skid forward at its lower edge. There is thus a relation between the plane of the bed with respect to the perpendicular and the angle of the flat with the bed. Along with this goes the very desirable resilient support of the upper front edge of the front flat, most important when applied progressively during the growing size of the pack and then subsequently during the working of the pack, when flats are applied at the back and coincidentally the front flats are dropped and turned during their fall.

An important thing is that the upper part of the flat at the front of the pack shall not fall forwardly while the pack is being made up and after the pack has been completed shall not fall before it reaches the front end of the pack.

Though the supporting straight surface 36 is described as horizontal, departure from the horizontal is permissible providing it does not result in skidding of the flats.

The pack is built up by successively placing flats from the rear, each flat placed causing the flats ahead of it to be advanced by a corresponding distance, until the front flat reaches the corner 45 at which the downward slope 39 or 39' begins. The flats must be supported against turning in either direction while the pack is being built up, by mechanical means at the back or either by gravity or by mechanical means in front.

When the direction of turning during fall is uniform danger of overlapping of one flat upon another is reduced and the extent of overlapping is also reduced. This character of turning movement is likely when the flats are sloped much backwardly and upwardly as they reach the front of the pack or when yielding front holding keeps the front upper surface of the front flat from turning forwardly until the lower edge strikes the surface 39.

Sliding down incline 39 or 39' tends to turn the front flat so that the face toward the rear of the pack is turned downwardly towards or against the slope at 39.

Figures 1 and 2 are alike in the latch mechanism for holding the rear flat. Spaced latches 59 are carried by arms 60 which extend over the run-in conveyor and are pivoted at 61 in line with perpendiculars to the upper edges of the faces of the rear flat 62.

The latch faces are cut away slightly, downward and away from the flats at 60' so that these relieved lower parts 60' of the latch faces will not rub on the flats. The latches are curved below at 63 so as easily to be lifted by the upper edge of each new flat in turn as it is placed by the face 32 of a dog 26.

Above each latch of the group along the length of the bed is located a stop 64 which engages successively with the top edge surface of 65 one of the rear flats in turn and which limits the extent of normal drop of the arm.

Each latch arm 60, and hence each latch is resiliently pressed downwardly in counter-clockwise direction, as illustrated, by gravity, with or without the assistance of a spring 65 tending to push upwardly a crank arm 66 rigid with the latch arm. The spring as shown surrounds a rod 67 pivoted to arm 66 at 68 and pressing against

the upper end 69 of a sleeve 70 through which the rod 67 extends.

Nuts 71 and 72 upon the rod set the extent of compression of the spring. Sleeve 70 is carried by strap 73 pivoted at 74 to adjusting arm 75. The arm 75 is secured to the shaft 76 and the latter can be turned to different angular positions by means not shown. The height of the latch engaging a rear flat held beneath it is thus adjusted without altering the spring pressure by which the latch may be pressed down on the top of the rear flat. This makes the spring pressure and range uniform, whatever the height of adjustment, i.e., whatever the widths of the flats which are being handled.

The direction of turning is not controlling but the allied avoidance of forward falling of the flats upon the bed before the flats are ready for discharge at the front of the pack tends to cause the flats to drop off of the forward bed edge rather than to fall at the tops outwardly and downwardly. When the upper front of the pack is not restrained, more slope of the faces of the flats is needed than with top front holding.

When it is desired to give but little slope to the flats and the flats consequently approach a vertical position instead of sloping decidedly upwardly and rearwardly, means are shown which can be used with any flat slope by which the upper front face of the forward flat of the pack may be restrained against moving forwardly farther than is required by the successive placings of additional flats at the back of the pack.

The extent of forward movement before the pack is relieved of a front flat to make up for a new flat at the back is determined by the point at which a front flat ceases to find support at the bottom and slides down the forward slope 39 or 39' at the end of what has been described as the straight portion of the bed or at which the flat is turned outwardly by hand or falls outwardly at the top.

The arms 60 can be lifted out of the way when not in use to some position exemplified by the dotted lines in Figure 1.

In Figures 2a, 2b and 2c, the latch arm shown is intended to be of the same character as the arm 60 in Figures 1 and 2 and the latch and approach curve also are much as in Figures 1 and 2. The end of the arm 60' carries pivotal support 71, Figures 2a, 2b, or 71', Figure 2c, for bars 78 and 78' which rest, 78 and 78' upon the upper edge 79 of the forward flat. The bars 78' are short and are intended for use in building up the pack, resting upon the front upper edge of each flat in turn until the forward extent of the flats is sufficient for the longer bars 78 to be used for the same purpose. The longer bars 78 not only take over restraint against the front flats falling forward at the point where the shorter bars will no longer reach but engage the upper front edges of the flats during the remainder of the building up of the pack and when the pack is full. Obviously more than two sets of bars can be used if desired. Any weight can be given the bars which is needed to carry out the required function.

The longer bars rest upon the upper front edge of each flat in turn and follow it down slightly as it falls until stopped by the upper rear edge of the new front flat.

The extent to which the bars 78 follow the falling front flat down depends upon the extent by which previously they had cleared the upper

front edge of the next to the front flat, and this in turn depends in part upon the height of the pivot point about which the bars 78 swing. For this reason lifting the point 80 at which the bars are pivoted in Figure 2a to the position 80' (Figure 2c) slightly increases the distance to which the bars will swing, while still in engagement with the upper front edge of the front flat before their engagement with it is broken.

The bars 78 and 78' swing about the axis of pin 81 (Figure 2b) supported in lug 82. The bars are held in place by cotters 83 and when not in use these bars are folded back as seen in Figure 2a, resting upon any supports 84 carried by the arm 60'.

As the front flat drops, its lower edge engages the surface 39 and is diverted outwardly while its upper edge is still prevented from moving outwardly as long as the bar 78 rests upon the edge of the outer flat and until the weight of the bar is taken up by the next to the outer flat.

In operation, if the flats be sloped enough so as reliably to lean backward throughout the pack (notwithstanding the compression at their lower edges due to friction) but not to skid, no provision is required to prevent them from falling down on the bed and, for the same reason they will not fall down forward at the point of discharge. If not, the bars hold the upper edges additionally or solely, and the bars prevent the upper parts from turning forward about the lower parts during the beginning of their falling movement. In the meantime, if the bars drop, the sloping surfaces 39 divert the lower edges of the flats forward, starting the lower edges turning forward about the upper edges and this turning movement is continued, because of continued engagement with the surface 39, even after the flats have fallen below the point at which the bars positively engage the upper edges and prevent them from moving forward.

With the extremely short lift of the latch at the rear required to permit a new rear flat to be placed, no appreciable longitudinal movement is given the holding bars during their movement.

Having thus described our invention what we claim as new and desire to secure by Letters Patent is:

1. The method of handling flats during the building up of a pack on a pack-annealing bed in which the flats are delivered by a run-in conveyor, which consists in mounting the flats one at a time at the back of the bed, sloping upwardly and rearwardly, in supporting them from a point back of the run-in conveyor, at the upper edge of the last flat, against falling rearwardly, and in supporting the upper edge of the front flat progressively against falling forwardly as the pack builds up and thus maintaining the upward and rearward slope.

2. The method of handling flats during the building up of a pack upon a pack-annealing bed in which the flats are delivered by a run-in conveyor which consists in mounting the flats successively on the bed, from the rear, sloping upwardly and rearwardly, in supporting them from a point back of the run-in conveyor, at the rear at the upper edge of the last flat, against falling rearwardly, and yieldingly retarding the upper edge of the front flat against falling forwardly and thus maintaining the upward and rearward slope, as the front flat advances from the rear to the front of the bed, until the pack shall have been built up.

3. The method of handling flats during the

building up of a pack upon a pack annealing bed in which the flats are delivered by a run-in conveyor and operating it as a pack which consists in mounting the flats successively on the

5 bed, from the rear, sloping upwardly and rearwardly, in supporting them from a point back of the run-in conveyor, at the rear at the upper edge of the last flat against falling rearwardly, and yieldingly retarding the upper edge of the front flat against falling forwardly, as the front flat advances from the rear to the front of of the bed, until the pack shall have been built up, continuing the retardation of the upper part of the front flat while successively dropping the 10 front flats from the front edge of the bed by reason of moving the pack forwardly beyond the front end of the bed as flats are inserted at the rear, and in guiding the bottom of each front flat outwardly as it falls while maintaining the same 15 yielding restraint upon the upper front surface of the flat.

4. In a pack-annealing system having a run-in conveyor, a pack-annealing bed upon which a pack is to be started, means for delivering flats 20 at the back of the bed successively, on edge, the pack comprising flats sloping upwardly and rearwardly, means for supporting the successive rear flats at the upper parts of their rear surfaces from a point back of the run-in conveyor and means adapted to engage and retard the upper 25 front of the growing pack, effective throughout the greater part of the width of the pack being built.

5. In a pack-annealing system having a run-in conveyor, a pack bed having an annealing pack of flats on edge thereon, a rear support for the upper part of the rear flat from a point back of the run-in conveyor, permitting placing of successive rear flats, and yielding means mounted upon but movable with respect to the rear support pressing the upper front part of the front flat rearwardly and downwardly against forward movement during the building up of the pack, comprising drag bars progressively engaging the 40 flats at different stages in the build-up of the pack at the back.

6. In a pack-annealing system having a run-in conveyor, an approximately horizontal bed support adapted to receive a pack to be annealed, 50 a pivoted retarder adapted to engage the upper front of the pack during the earlier part of building up the pack, a second pivoted retarder adapted to engage the upper front of the flats during the later part of the building up of the pack and a support for the retarders, extending forwardly from a point back of the run-in conveyor.

7. A pack annealing bed having a run-in conveyor, means for delivering flats to the bed on edge, sloping upwardly and rearwardly, a yieldable latch adapted to engage the upper rear of the flat, retarding means engaging the upper front of the front flat of the pack, while the pack is being assembled and a support common to the latch and to the retarding means and reaching forwardly from a point back of the run-in conveyor.

8. A pack annealing bed, means for delivering flats to the bed on edge, sloping upwardly and rearwardly, a yieldable latch adapted to engage in turn the upper rear of each flat, retarding means engaging the upper front of the front flat of the pack, while the earlier part of the pack is being assembled, a support for the retarding means and additional retarding means mounted

upon the same support and adapted to engage the upper front of the front flat of the pack during the assemblage of the later part of the pack.

9. In a pack annealing system having a bed, a run-in conveyor and means for delivering a flat from the conveyor upon the bed on edge in position sloping upwardly and rearwardly, a latch adapted to engage the upper rear of the flat and an arm carrying the latch and supported in the rear of the conveyor and reaching over it, one of the parts, the latch or the arm being yieldable to permit the flats to be forced past the latch, one by one to latching position.

10. In a pack annealing system having a bed, a run-in conveyor and means for delivering a flat from the conveyor upon the bed on edge in position sloping upwardly and rearwardly, a latch yieldable in one direction adapted to engage the upper rear of the flat, an arm carrying the latch and supported in the rear of the conveyor and reaching over it and means carried by the arm for retarding the upper front flat of the pack during building up of the pack.

11. In a pack annealing system, a run-in conveyor, kick-off means for removing a flat laterally therefrom, an apron sloping downwardly from the conveyor, a pack bed, means for delivering a flat from the apron to the bed in position at the rear of the bed, on edge, sloping upwardly and rearwardly, a latch arm movably mounted back of the run-in conveyor, reaching over it, and a latch upon the arm which latch engages the flats successively at their upper rear edges as they are delivered.

12. In a pack annealing system having a bed, a run-in conveyor and means for delivering a flat from the conveyor upon the bed on edge in position sloping upwardly and rearwardly, a latch yieldable in one direction adapted to engage the upper rear of the flat an arm carrying the latch and supported in the rear of the conveyor and reaching over it and means permitting movement of the arm upwardly and away from the pack to take the arm out of the way.

13. In a pack annealing system having a bed, a run-in conveyor and means for delivering a flat from the conveyor upon the bed on edge in position sloping upwardly and rearwardly, a latch yieldable in one direction adapted to engage the upper rear of the flat, an arm carrying the latch, movably supported in the rear of the conveyor and reaching over it, means carried by the arm for retarding the upper front flat of the pack during building up of the pack, the support permitting movement of the arm upwardly and away from the pack to take the arm out of the way.

14. In a pack annealing system, a pack bed, a run-in conveyor for flats, delivery means including a kick off for placing the flats successively on edge, sloping upwardly and rearwardly at the rear of the pack, pivoted latch means engaging the upper rear edges of the successive rear flats as placed, yielding to permit placing of the suc-

cessive rear flats and supported at the rear of the run-in conveyor to reach over the run-in conveyor and the delivery means and means for adjusting the height of the latch at the flats in agreement with the widths of the flats.

15. In a pack annealing system, a run-in conveyor, kick-off means for removing a flat laterally therefrom, an apron sloping downwardly from the conveyor, a pack bed, means for delivering a flat from the apron to the bed in position at the rear of the bed, an edge, sloping upwardly and rearwardly, a latch arm movably mounted back of the run-in conveyor, reaching over it, a latch upon the arm which latch engages the flats successively at their upper rear edges as they are delivered, a pivot for the arm, a second arm and connections forming a bell crank lever with the first arm and operating means for the lever including a spring through the bending of which the latch is given a resilient capacity to yield upwardly.

16. In a pack annealing system, a run-in conveyor, kick-off means for removing a flat laterally therefrom, an apron sloping downwardly from the conveyor, a pack bed, means for delivering a flat from the apron to the bed in position at the rear of the bed, on edge, sloping upwardly and rearwardly, a latch arm movably mounted back of the run-in conveyor, reaching over it, a latch upon the arm which latch engages the flats successively at their upper rear edges as they are delivered, a pivot for the arm, a second arm and connections forming a bell crank lever with the first arm and operating means for the lever including a shaft, an operating arm on the shaft, a rod connected with the lever, a spring carried by the rod, and connections between the rod and the operating arm permitting variant compression of the spring and providing additional compression of the spring when placing of a flat lifts the latch and arm.

17. In a pack annealing system, a run-in conveyor, kick-off means for removing a flat laterally therefrom, an apron sloping downwardly from the conveyor, a pack bed, means for delivering a flat from the apron to the bed in position at the rear of the bed, on edge, sloping upwardly and rearwardly, a latch arm movably mounted back of the run-in conveyor, reaching over it, a latch upon the arm, which latch engages the flats successively at their upper rear edges as they are delivered, a pivot for the arm, a second arm and connections forming a bell-crank lever with the first arm, a threaded rod connected with the lever, a sleeve about the rod, a stop upon the rod, a spring between the stop and the upper end of the sleeve, a nut engaging the thread and by its position determining the normal compression of the spring and means for operating the sleeve to lift the arm and to allow it to lower so as to adapt the latch height to the widths of the flats handled.
